Primary Examiner — Melody N Brown(74) *Attorney, Agent, or Firm* — Fei Hung Yang(57) **CLAIM**

The ornamental design for an electric vehicle, as shown and described.

DESCRIPTION

FIG. 1 is a front and right side perspective view of an electric vehicle showing my new design;

FIG. 2 is a rear and right side perspective view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The portions of the electric vehicle shown in broken lines represent unclaimed subject matter that form no part of the claimed design.
